UNITED STATES PATENT OFFICE.

EMANUEL G. KOHOUT, OF NEW YORK, N. Y.

KNOCKDOWN BOX.

1,001,051.

Specification of Letters Patent. Patented Aug. 22, 1911.

Application filed April 11, 1911. Serial No. 620,358.

To all whom it may concern:

Be it known that I, EMANUEL G. KOHOUT, a citizen of the United States, and residing at New York, in the county of New York 5 and State of New York, have invented certain new and useful Improvements in Knockdown Boxes, of which the following is a specification, such as will enable those skilled in the art to which it appertains to 10 make and use the same.

This invention relates to what are known as foldable or knockdown boxes, and the object thereof is to provide an improved device of this class which is simple in construction and comparatively inexpensive and which may be used for many purposes; a further object being to provide a box of the 15 class specified which may be compactly folded together in the smallest possible 20 space for convenience in packing, or shipping from one point to another.

The invention described and claimed herein is an improvement on that described and claimed in a prior application for Letters Patent of the U. S. filed by me January 23rd, 1911, Serial No. 604,071, and said invention is fully disclosed in the following specification, of which the accompanying drawing forms a part, in which the separate 25 parts of my improvement are designated by suitable reference characters in each of the 30 views, and in which:

Figure 1 is a perspective view of a knockdown box made according to my invention 35 and showing the cover thereof open. Fig. 2, a plan view showing the parts of the box folded together;—Fig. 3, a diagrammatic section on the line 3—3 of Fig. 2;—and, Fig. 4, a similar section on the line 4—4 of 40 Fig. 2.

My improved knockdown box *a* as shown in the drawing is rectangular in form and square or approximately square in plan, or horizontal section. The said box may be 45 oblong in form in plan or horizontal section, if desired.

The box *a* comprises a bottom *b*, two opposite side members *c* hinged to the bottom *b*, and two other opposite side or end members *d* also hinged to the bottom *b* and a cover *e* hinged, in the construction shown, to one of the side members *c*. All the parts 50 of the box, as above described, are composed of sheet metal, in the form of construction shown, and all the side or side and end 55 portions are divided horizontally and cen-

trally in the top and bottom portions which are hinged together at *f*, and said side or side and end portions are hinged to the bottom *b*, as shown at *f*².

The hinges at *f* are formed so that two opposite side members, as *c*, will fold outwardly centrally thereof, as indicated at *c*², and the other two opposite side or end members, as *d*, will fold inwardly, as indicated at *d*², and the hinges at *f*² are so formed that two of the side members, as *c*, will fold outwardly, while the other two side or end members, as *d*, will fold inwardly.

The hinges at *f* consist of continuous rods *f*³, the lengths of which are equal to the horizontal dimensions of the side or side and end members, and these rods are placed in keepers stamped in the material of said side or side and end members when the hinges or 70 the separate parts of the hinges *f* are formed, and one part of the hinges *f* is formed in connection with one part of the side or side and end members and the other part of said hinges is formed in connection with the 75 other part of said side or side and end members, in the operation of stamping said side or side and end members out of sheet metal.

The hinges *f*² by which the side or side and end members are connected with the 80 bottom *b* are formed in a manner similar to the hinges at *f*, said hinges at *f*² consisting of rods placed in keepers formed when the 85 separate parts of said hinges are stamped out, and said separate parts of said hinges 90 being also formed in connection with the bottom *b* and in connection with the side or side and end members.

The cover *e* is hinged to one of the side members, as shown at *e*², and is adapted to 95 fold over on and inclose the box when the separate parts of said box are in the position shown in Fig. 1.

Placed in the top of the box, or in the top 100 of the side or side and end members, is a frame *g* composed of a stiff wire or rod bent into the exact form and dimensions of the top of the box or the body thereof, and this frame is held in place by keepers *g*² formed by folding the top edges of the side or side 105 and end portions of the box.

Any suitable means may be provided for holding the cover *e* in a closed position, and the operation of folding the separate parts 110 of the box together, as shown in Figs. 2 to 4 inclusive, will be readily understood from the foregoing description, when taken in

connection with the accompanying drawing and the following statement thereof. In this operation the cover *e* is first raised, as shown in Fig. 2. The side members *c* are bent outwardly centrally thereof, and at the same time the side or end members *d* are bent inwardly centrally thereof and this movement is continued until the said side or side and end members are compactly folded together on the bottom of the box, as shown in Figs. 2 to 4 inclusive, and the cover *e* is then folded thereon as is also shown in said figures. In this operation the top edges of the side members *c* and side or end members *d* remain in connection with the frame *g*, as will be readily understood, and the top corners of the box move downwardly and vertically, and whenever it is desired to raise the parts of the box into position for use, as shown in Fig. 1, the cover *e* is first raised and the inner or top edge portions of the side members *c* and side or end members *d* are grasped or raised into the position shown in said figure, after which the cover *e* is lowered and secured.

With this construction it is not absolutely necessary to provide other means for securing the corners of the side or side and end members *c* and *d* together so as to hold said members in an upright position, for the reason that when the box has once been filled with the desired contents, the said side or end members *d* cannot fold inwardly, and the side members *c* can therefore not fold outwardly and said side or side and end members will remain in the proper position, as shown in Fig. 1. My invention is not limited, however, to the particular construction of the corner parts of the box or the connection thereof, and changes in and modifications of these features of construction may be made, within the scope of the appended claims, without departing from the spirit of my invention or sacrificing its advantages.

Having fully described my invention,

what I claim as new, and desire to secure by Letters Patent, is:-

1. A knockdown box comprising a bottom, side or side and end members hinged to the bottom, and a cover hinged to one of said side or side and end members, said side or side and end members being divided centrally and horizontally into two similar parts hinged together, this connection being such that two opposite side or side and end members will fold outwardly, and the other two opposite side or side and end members will fold inwardly, and the hinged connection of the side or side and end members with the bottom being correspondingly formed, and said side or side and end members being provided at the top and at the corners thereof with a folding connection.

2. A knockdown box comprising a bottom, side or side and end members hinged to the bottom, and a cover hinged to one of said side or side and end members, said side or side and end members being divided centrally and horizontally into two similar parts hinged together, this connection being such that two opposite side or side and end members will fold outwardly, and the other two opposite side or side and end members will fold inwardly, and the hinged connection of the side or side and end members with the bottom being correspondingly formed, and said side or side and end members being provided at the top and at the corners thereof with a folding connection, consisting of keepers at the top of said side or side and end members and a wire or rod frame placed in said keepers.

In testimony that I claim the foregoing as my invention I have signed my name in presence of the subscribing witnesses this 10th day of April 1911.

EMANUEL G. KOHOUT.
